US00D496362S1

(12) **United States Design Patent** (10) Patent No.: **US D496,362 S**
Ozolins et al. (45) Date of Patent: **** Sep. 21, 2004**

(54) **MULTI-PANEL COMPUTER DISPLAY**

(75) Inventors: **Helmars E. Ozolins**, Orient, NY (US); **Masamichi Udagawa**, New York, NY (US); **Alfonso Castagna**, Etobicoke (CA); **Christopher J. H. Stewart**, Toronto (CA); **Alexander Chong**, Thornhill (CA); **Sigrid G. Moeslinger**, New York, NY (US)

(73) Assignee: **Bloomberg LP**, New York, NY (US)

(**) Term: **14 Years**

(21) Appl. No.: **29/166,843**

(22) Filed: **Sep. 3, 2002**

(51) LOC (7) Cl. **14-02**

(52) U.S. Cl. **D14/375**

(58) Field of Search **D14/371-376, D14/125-129; 248/917-924; 349/12, 1, 2, 11, 62; 345/104, 156, 168, 173, 901-905, 87, 1.1, 1.3; 348/180, 184, 325, 739, 383; 361/681**

(57) **CLAIM**

We claim the ornamental design for a multi-panel computer display, as shown and described.

DESCRIPTION

FIG. 1 is a front perspective view of our design for a multi-panel computer display.

FIG. 2 is a rear perspective view thereof.

FIG. 3 is a front elevation thereof.

FIG. 4 is a rear elevation thereof.

FIG. 5 is a right side view thereof. The left and right sides of our design are mirror images of each other.

FIG. 6 is a top view thereof; and,

FIG. 7 is a bottom view thereof.
